UNITED STATES PATENT OFFICE.

ROBERT L. ROCKWELL AND ERNEST G. HOWE, OF SEATTLE, WASHINGTON, ASSIGNEES,
BY MESNE ASSIGNMENTS, TO ERNEST G. HOWE, TRUSTEE, OF SEATTLE, WASH-
INGTON.

AUTOMATIC SEMAPHORE SIGNAL SYSTEM.

Application filed June 12, 1918. Serial No. 239,673.

To all whom it may concern:

Be it known that we, ROBERT L. ROCK-
WELL and ERNEST G. HOWE, citizens of the
United States, residing at Seattle, in the
5 county of King and State of Washington,
have invented a new and useful Improve-
ment in Automatic Semaphore Signal Sys-
tems, of which the following is a specifica-
tion.

10 This invention relates to new and useful
improvements in electrically operated sema-
phore signal systems intended to control the
movement of cars or trains along a double
or single track railway, being particularly
15 applicable to mono-rail railway construc-
tion.

The object of this improvement is to pro-
vide a signal system that is entirely electric-
ally independent of the track, thereby mak-
20 ing it applicable to railways using either
steam, compressed air, direct or alternating
electric current, or other sources of motive
power.

A further object resides in the provision
25 of a semaphore signal system adapted to ac-
tuate an automatic train stop mechanism
should the danger semaphore indications be
disregarded for any reason.

A still further object resides in the sim-
30 plicity of construction and comparatively
low installation cost, yet embodying posi-
tiveness and reliability in operation.

A still further object contemplates all
35 semaphore arms being normally set to
danger, thus requiring the car or train to
effect clear indications before such car or
train can proceed past the several semaphore
stations.

An additional object is to provide for the
40 control of a multiplicity of semaphore sta-
tions by a single primary circuit relay in
turn controlled by the operation of two cur-
rent reversing switches to be actuated by
45 cars or train operating within the signal-
ized section of track.

A final object is to effect danger indica-
tions of semaphore stations on either side
of movable track sections whenever such
track sections are not in the proper oper-
50 ating position and securely locked in place.

The invention consists in the novel con-
struction, adaptation and combination of
parts as will be more fully described in the
following specification, illustrated in the

accompanying drawings, and finally point- 55
ed out in the appended claims.

In the drawings, Figures 1, 2, 3, 4, 5, 6,
7 and 8 are elementary diagrams of a signal-
ized section of track and the electrical cir- 60
cuits employed to effect the semaphore po-
sitions indicated for the various car posi-
tions shown.

Fig. 9 is a diagram showing the method
of winding the differential relays used in
this system. 65

Fig. 10 is a diagram showing the mechani-
cal arrangement required to operate one of
the battery reversing switches.

Fig. 11 is a section taken along line D—D
of Fig. 10 to show the relation between par- 70
ticular parts of the reversing switch oper-
ating mechanism.

Fig. 12 is a side elevation showing the
type of car, and its supporting structure to
which this system of semaphores is particu- 75
larly applicable.

Fig. 13 is a plan view of one of the trucks
of such a car showing the arrangement of
air-brake rods and levers.

Fig. 14 is a diagram of the air-brake 80
mechanism, automatic stop equipment and
the arrangement of the battery reversing
switch and the device mounted on the car
to actuate it.

Figs. 15, 16, 17, 18, 19, 20, 21 and 22 are 85
diagrams showing more particularly the de-
tail electrical connections that may be used
to effect the semaphore indications for va-
rious positions of a car proceeding along a
signalized section of track. 90

Figs. 23 and 24 relate to semaphore arm
indications and the electrical circuits used
when one car follows another through such
a signalized section.

Figs. 25 and 26 are diagrams of sema- 95
phore arm positions and the electrical cir-
cuits employed when controlling a plurality
of semaphore stations from a single battery
reversing switch and primary circuit relay.

Figs. 27 and 28 are diagrams showing 100
particularly the relative positions of bat-
tery reversing switches and semaphore sta-
tions and the electrical circuits involved at
the ends of the signal system.

Figs. 29 and 30 are track and electric cir- 105
cuit diagrams showing semaphore indica-
tions and a circuit auxiliary to the signal
system proper required to produce the

danger signals indicated when movable track sections are in dangerous positions.

- Referring more particularly to the drawings, the fundamental physical arrangement 5 of the system contemplates all semaphores at danger position, as shown in Fig. 1, when there are no trains on the signalized sections of the track, hence a car entering the electrified section must clear its way in order 10 to proceed. This is done by reversing the terminals of the various batteries in a so-called primary relay circuit by means of suitably constructed battery reversing switches indicated in Fig. 1 by numbers 180, 15 280, 380, 480 and 580. This figure indicates a complete system, consisting of five semaphore stations and a corresponding number of battery stations in the primary relay circuit. The car is shown in the act of reversing the first battery by means of switch 180. This will immediately clear semaphores 100 and 200, as shown in Fig. 3. The car can then proceed past semaphore station 100 and continue its travel toward semaphore station 200, which also indicates clear, 20 operates reversing switch 280, which moves semaphore 100 to danger, keeps semaphore 200 at clear and clears semaphore 300 as indicated in Fig. 5. The semaphore positions are such that the car is at liberty to either proceed in the original direction or back past semaphore station 200, in which event it would reverse battery switch 280 and the semaphore positions would again be as 25 indicated in Fig. 3. As Fig. 5 indicates, while proceeding through the electrified sections, if no other cars are within a prescribed distance, the car will have a clear signal in front of it and a clear signal behind it, which gives it full liberty of motion in either direction. In case another car was moving between semaphore stations 300 and 400, the car sighted, upon passing semaphore station 200 and reversing switch 280, will 30 give semaphore positions as indicated in Fig. 7, semaphore station 300 being at danger, while semaphore station 200 is at clear. The leading car in this case has a clear signal at station 400 but a danger signal at station 300; therefore the leading car is at liberty to proceed on its way along the track. The following car, however, cannot 35 pass station 300 because of the automatic stop levers 340 being set in such a position that it will effect the shutting off of motive power and the setting of air and electric brakes in case the signal be disregarded by the following car. It is intended that this elementary system shall be used only for 40 double track systems or a system of the loop type where cars operate only in one direction. The system, however, may be modified by a few additions, so that it is applicable to track sections on which cars 45 are operating in both directions. These ad-

ditions will be hereinafter more fully described. It now remains to show how these various semaphore positions are obtained for the car positions indicated in Figs. 1, 3, 5 and 7. The electrical connections required 70 to bring about the desired operation of the signals are shown in Figs. 2, 4, 6 and 8.

Referring to Fig. 2, it will be noticed that the primary relay circuit provides a series of closed electrical circuits, consisting of a 75 number of batteries 21, 22, 23, 24 and 25, relay windings 71, 41, 32, 42, 33, 43, 34 and 72, and connecting wires 51, 52, 53, 54, 60, 61, 62, 63, 64 and 65. Fig. 1 shows the car about to operate a device 180 whose function 80 is to reverse battery 21 of Fig. 2. It will be noticed also that although the various circuits composing the primary relay circuit are complete in every detail electrically, no current will flow if the electromotive force 85 of each battery is the same. The first of these circuits comprises battery 21, battery 22, differential relay winding 41, simply relay winding 71 and connecting wires 51, 69 and 61. It is evident that with the present 90 connections no current can flow in this circuit and, therefore, the relay armature 103 and 203 of semaphore stations 100 and 200 are held by gravity against the lower contacts which will give in all cases the danger 95 indication for their respective semaphores.

In this primary relay circuit for instance, the current in amperes I is given by the well known formula: I equals E divided by R where the effective electromotive force E is 100 always the algebraic sum of all the E. M. F's acting in the circuit, and the total resistance R includes the internal resistance of the batteries themselves, that of the relay windings and of the line wires between the stations. Since batteries 21 and 22 in Fig. 1 are opposing each other in their efforts to force current through the circuit described, it is evident that in this case E is equal to zero in the above formula; therefore, the 110 current must also be zero. With no current flowing through the relay windings, gravity holds the relay armatures 103 and 203 against the lower contacts, which completes the local motor circuits for moving the semaphore from the clear to the danger position, as will be described later.

An important feature of this system is the arrangement of the relay windings to the various battery stations. It will be noticed 120 that the first relay in order from left to right whose winding is indicated by 71 and armature by 103, is of the simple type. This relay is located at semaphore station 100 which is a considerable distance in the direction indicated from the battery reversing switch 180. At semaphore station 200 it will be noticed that the relay consists of two 125 separate windings 41 and 32. The armature 203 being actuated by an iron core common 130

to the two windings as shown in Fig. 9 which, however, is numbered to correspond to semaphore station 300.

After reversing battery 21, it will be noticed in Fig. 4 that current will flow between battery stations 21 and 22 through the following devices; battery 21, connecting wire 60, relay winding 71, connecting wire 61, relay winding 41, battery 22 and connecting wire 51, back to the negative terminal of battery 21. The arrows indicate the direction of current flow. This flow of current energizes relay winding 71 and one winding 41 of the differential relay at station 200. The design of this relay is such that with this current flow through the single winding 41, sufficient magnetization is produced to raise the armature 203 to the upper contact. It will be noticed that with the limit switches 109 and 209 in the positions indicated in Fig. 2, that when relay armatures 103 and 203 are raised current will flow from the semaphore station batteries 101 and 201 as follows: At station 100 from battery 101, through relay armature 103, motor field winding 106, limit switch 109, motor armature 113, back to the negative terminal of battery 101. At station 200 the current flow is from battery 201, through relay armature 203, field coil 206, limit switch 209, motor armature 213, to the negative terminal of battery 201. The resulting rotation of armature 113 and 213 is such in each case that the semaphore arms 100 and 200 will be moved to the clear position. The result is that as the car leaves battery station 21 and approaches semaphore station 100 it finds upon arriving at that semaphore station a clear signal which indicates that it may proceed to the next station or at least within sight of the next semaphore in safety. In passing semaphore station 200, battery 22 will be reversed by means of reversing switch 380, leaving the circuits in the condition indicated in Fig. 6. With battery 22 reversed, the first circuit between batteries 21 and 22 above referred to will have an effective electromotive force equal to zero because batteries 21 and 22 are again opposing each other; therefore, no current will flow in that circuit and relay windings 71 and 41 allow armatures 103 and 203 to drop to the lower contacts. This really takes place at station 100 but at station 200 it will be noticed that relay coil 32 is now effective in magnetizing the core and holding armature 203 against the upper contact, therefore, maintaining semaphore 200 in the clear position. At station 100, however, when armature 103 is moved by gravity against the lower contact, current will flow from battery 101 through relay armature 103, field coil 117, limit switch 109, armature 113, back to the negative terminal of battery 101.

It must be remembered that limit switch

109, during this process, is in the position indicated in Fig. 4. As soon as the semaphore is set to the danger position the limit switch is automatically thrown from the upper contact to the lower contact, which stops the motor and provides another circuit through field coil 106, armature 113, limit switch 109, relay armature 103 and battery 101 whenever relay coil 71 is again magnetized. It is to be observed that as the magnetizing of the core, required to hold armature 203 in a raised position is shifted from coil 41 to coil 32 by the reversing of battery 22, the polarity of magnetization of the core is still in the original direction—that is, using Fig. 9 to represent the electrical circuits with battery 22 in the original position and coil 41 producing the magnetizing action, the polarity of the coil, according to the well known Right Hand Rule, will be S at the lower end and N at the upper. Upon reversing battery 22, which gives zero current in coil 41 and full current in coil 32, the polarity of magnetization is still S at the bottom and N at the top. It is evident then that there is no chance for hysteretic lag in the magnetization of the coil, which might be a disadvantage in case it was necessary to reverse the polarity as the magnetizing action was changed from one relay coil to the other. It is also evident that in the case of a highly inductive circuit this maintenance of the original polarity would allow an appreciable time for current to build up in the new circuit still maintaining the armature in the raised position, which is a desirable feature in the operation of a device upon which so much depends.

With a second car between semaphore stations 300 and 400 it is evident that before this second car entered the signalized section of track the batteries were all connected relative to the line wires, as shown in Fig. 8 at battery station 24. As this car proceeded from station to station it reversed the several batteries, viz: 21, 22 and 23 in order, leaving them in the position indicated in Fig. 2. As the car, the travel of which we have been discussing from station to station, passes station 200, reversing battery 22 by means of switch 280, two circuits are effective in the primary relay circuit to produce the clear signal at semaphore station 200, danger at 300 and clear at 400 as shown in Fig. 8. The first circuit comprises battery 22, relay winding 32, connecting wire 62, relay winding 42, battery 23, connecting wire 52, back to the negative terminal of battery 22. The magnetization of coil 32 raises relay armature 203, giving a clear signal at semaphore station 200, likewise current flow through battery 24, relay winding 43, connecting wire 63, relay winding 33, battery 23 and connecting wire 53, raises armature 403 and gives a clear signal at semaphore station

400. At semaphore station 300 it will be noticed that the current from these two circuits magnetizes the iron core by coil 42 for one polarity and by coil 33 for the opposite 5 polarity. The result is zero effective magnetization of the core, and armature 303 is allowed to drop to the lower contact which we have shown in all cases will produce a danger indication of the semaphore arm at 10 that station.

Referring to Fig. 9, which is intended to 15 convey these principles more clearly, it will be noticed that the conductors comprising coils 42 and 33 are wound around the core 20 after first being laid side by side. The result of this arrangement is such that the magnetizing action produced by one coil is almost perfectly neutralized by the magnetizing action of the other coil which is in 25 the reverse direction. In this figure the relay contacts 304 and 319 are shown consisting of spring brass tipped with silver. The corresponding contact pads on armature 303 are also of silver. In making contact in 30 either direction the result is a slight scraping action between the contacts, which insures good electrical connection. This is standard practice for circuits of this nature and is not original, hence forms no part of this invention.

In this system it will be noticed that the 35 successful operation of the system will depend upon the effectiveness of the switch, the function of which is to reverse the battery at the various battery stations as the car proceeds along the track. In Fig. 10 is shown in diagram a switch of this nature. In Fig. 14 is shown the relative position of the switch and the operating device 78 on the car truck 79 which throws lever 3' of Fig. 10 in either direction, depending upon the direction of motion of the car. The device 78 on the car will be referred to as an impact shoe, the construction of which forms 40 the subject of a copending application of even date. The design of this shoe is such that it will insure, without unnecessary shock or jar to the reversing switch, a complete movement of the operating lever 3' for either direction of motion of the car irrespective of the loading of the car and, therefore, the height of the truck frame 79 above the reversing switch. This is necessary because the truck frame 79 will assume 45 different relative positions for different loads on the car platform due to the compressing of the truck springs. The combination of impact shoe and reversing switch as indicated requires that the battery be completely 50 reversed in the electrical circuit of which it forms a part by a movement of the operating lever 3' of about 45° in either direction. This is made possible by means of the arrangement of contact segments 15, 16, 17 and 18, and contact fingers 7, 8, 9 and 10. 55

Tracing the electrical connection shown in Fig. 10, the current flow will be from the positive terminal of battery 22, through wire 1, contact finger 9, contact segment 17, contact finger 10, connecting wire 4, coil 32, 70 wire 3, contact finger 8, contact segment 16, contact finger 7, wire 2, back to the negative terminal of battery 22. Upon actuating this switch 45° to the right, as indicated in Fig. 10 by the dotted outline of the reversing 75 lever 3', each of the contact segments 15, 16, 17 and 18 will be moved 45° from their present position to the right. The result is that contact segment 16 connects contact 80 fingers 8 and 9 electrically while contact fingers 7 and 10 are connected by contact segments 15 and 17 and connecting wire 5. The current flow through coil 32 was previously from left to right. With this new position of the reversing switch segments the 85 current flow will be from battery 22, through 1, 9, 16, 8, 3, to the right terminal of coil 32, through coil 32 from right to left, then through 4, 10, 17, 5, 15, 7 and 2, back to the negative terminal of battery 22. It is evident 90 that if lever 3' be actuated again to the right that contact segment 15 would then occupy the same position as contact segment 16 occupies in Fig. 10 and, therefore, the current flow through coil 32 would be from left to right, the reverse of its former direction. 95 This shows that the device effects one reversal of the battery electrically for each operation of the reversing lever 3' from the vertical to the extreme right position. With the reversing switch set, as shown in Fig. 10, corresponding to current flow through coil 32 from left to right, if operating lever 3' be moved 45° to the left, contact segment 17 will connect electrically contact fingers 100 8 and 9 and contact fingers 7 and 10 will be connected by contact segments 16, wire 6, and contact segments 18. The current flow will then be from the positive terminal of battery 22, through 1, 9, 17, 8, 3, to the right terminal of coil 32, through coil 32 from right to left, then through 4, 10, 18, 6, 16, 7 and 2 back to the negative terminal of battery 42. If the operating lever 3' is again 110 moved 45° to the left, segment 18 will connect contact fingers 9 and 10 and segment 17 will connect contact fingers 7 and 8. The current flow will then be from the positive terminal of battery 22, through 1, 9, 18, 10, 4, 32, 3, 8, 17, 7, and 2, back to the negative 120 terminal of battery 22, giving current flow from left to right through coil 32 or in the reverse direction previously taken by the current. It is evident that coil 32 may be any electrical equipment whatever. In this 125 case it would be one of the relay windings included in the primary relay circuit. From this discussion it is evident that whenever the operating lever 3' is moved in either direction it effects one reversal of the battery 130

with reference to the electrical equipment it is supplying current to. It remains to describe more fully the mechanical operation of this switch.

5 Fig. 10 is not intended to represent a complete mechanical contrivance but is intended to show in diagram the various mechanical elements which are deemed necessary for the satisfactory operation of the battery reversing switch proper. Mounted rigidly 10 upon a common shaft 14' are:—

First, the reversing switch itself, consisting of contact segments 15, 16, 17 and 18 electrically connected as shown by conductors 5 and 6. These segments are supported by a disk of insulating material which provides intervals of insulation 11 between the several contact segments insulating the contact segments from each other and from 20 the shaft. These intervals of insulation are provided of liberal proportions to eliminate the short circuiting of the battery each time the switch is operated 45° to the right or left for it is evident that a movement of 25 22½° in either direction from the position shown will result in placing contact fingers 7 and 9, which are connected to the terminals of the battery, directly in the center of the insulating intervals between segments. If 30 this insulating interval is not sufficient to prevent contact fingers 7 and 9 from making contact with any single segment, such as 16, for a movement to the right from the position in Fig. 10, or segment 16, contact 35 finger 8, and segment 17, for movement to the left, the battery would be short circuited every time it is reversed in the circuit of which it forms a part. The result would be not only a useless consumption of 40 electrical energy but excessive wear due to sparking at each point where the short circuit would be open. With the arrangement shown, this objectionable feature is eliminated while the switch itself loses nothing 45 in effectiveness.

Second, a spacing wheel 22' provided with eight projections and, therefore, eight intervals. This wheel is used to effect a complete definite movement of the reversing switch proper either to the right or to the left. If for any reason the operating lever 3' should move through an angle less than 45° and more than—say 25°, the spacing wheel with its attachment will complete the 50 45° movement required for the successful operation of the switch. This is made possible by means of the attachment shown consisting of an arm 28' working around a fixed pivotal point 29', which supports at 55 its other extremity a roller 23' by means of pin 24'. This end of the lever may be forked to more conveniently accommodate the roller, and it is the intention of the diagram to represent such a combination. The 60 roller is held firmly against the spacing 65

wheel by means of the double helical spring 25' which is in compression between the rigid support 26' and lever 28'. 27' is a pin pivoted at its lever end and passing through the fixed support 26' to keep the spring while 70 in compression in definite alignment between the lever 28' and support 26'. It will also serve in the case of breakage of one of the springs, to prevent the parts from leaving the position in which they may still be, in 75 a measure, effective.

Third, a ratchet wheel 7' used to rotate the shaft to the left by means of pawl 5' attached to operating lever 3' by means of a pin 6', and another ratchet wheel 8' used 80 to turn the shaft to the right by means of pawl 5'' which is also supported by pin 6'. Spring 4' supported at its center by lever 3' serves to keep pawls 5'' and 5' in mesh with their respective ratchets. In order to 85 turn the shaft 45°, say to the left, and let it remain there, in using this device it is necessary that pawl 5'' be kept from engaging the ratchet projection near which it is shown in the diagram, when the lever 3' returns to 90 the vertical position. This is effected by means of a plate 9' rigidly fixed to the supporting frame and held between the arc of travel of pawl 5'' and the ratchet wheel 8' which it engages. A similar plate 9'' is 95 held between the arc of travel of pawl 5' and ratchet wheel 7' which it engages. With this arrangement it is evident that as operating lever 3' moves from the vertical position to the left, the pawl 5'' will engage ratchet 7' and the shaft 14' will be rotated through the required 45°. During this movement of the arm 3', plate 9' will raise pawl 5'' clear of the ratchet wheel so that on 100 the return of arm 3' to the vertical position it will be kept from engaging the ratchet projection opposite, which is shown in the diagram, and will engage the next one in order to the right when the lever 3' returns 105 to the vertical position. In case the arm is moved to the right, as indicated by the dotted outline in Fig. 10, pawl 5' will be prevented from engaging the ratchet projection directly under it by plate 9'' when lever 3' returns to the vertical position. 110

Fig. 11 is a top view, showing the relative positions for pawls 5'' and 5', ratchets 7' and 8', and plates 9' and 9''. The object of roller 1', supported by pin 2' at the free end of arm 3', which is forked to receive it, is 115 to prevent unnecessary wear and tear of this part of the signal equipment while being operated by the impact of shoe 78 of Fig. 14.

Lever arm 3' is arranged to rotate about 125 shaft 14' and is not rigidly connected to it. In order to keep arm 3' in a vertical position at all times so that the device is operative in either direction, it is necessary that some device be provided which will return 130

it automatically to the vertical position and, without undue oscillation, keep it in that position. This is preferably effected by means of two wing-like projections 13'' and 13' at the bottom of the arm working in conjunction with a lever 15' pivoted at one end on the pin 16', the other end of which is forked and carries a roller 21' by means of pin 21''. This roller engages the wing-like projections 13'' and 13'. Lever 15' is forced upward with the required pressure by means of two helical springs 19' in compression between the support 20' and the shoulder of the guide pin 18' pivoted at its upper extremity by pin 17' which passes through arm 15'. It will be seen from this arrangement that when lever 3' is moved to the right, lever 15' will be forced at its free end vertically downward by means of the wing-like projection 13'', which results in still greater compression of spring 19'. When lever 3' is released it is evident that the curved edge of projection 13'' will serve in conjunction with lever 15' and spring 19' to return lever 3' to the vertical position. When the lever is operated to the left, projection 13' performs a similar service.

The automatic emergency equipment to work in conjunction with this system of signals and stop levers provided at each semaphore station may consist of any combination that can be operated by the automatic stop levers to effect a stoppage of the car in case it proceeds past a semaphore station set at danger. A combination for accomplishing this result may consist essentially of an electrically re-set air valve and electric switch mounted on one of the trucks of each car or train to effect the shutting off of motive power and the setting of air and electromagnet brakes whenever the operating handle of the combination valve-switch engages an automatic stop lever placed on each side of the track at each semaphore station and controlled mechanically by the semaphore operating mechanism. The arrangement is such that the operating handle of the combination valve-switch will engage one of the automatic stop levers of a semaphore station set at danger should the car for any reason attempt to pass such a station.

At all semaphore stations indicating clear the operating mechanism will place the automatic stop levers in such a position that they cannot engage the operating handle of the combination valve-switch, hence in passing such a station the automatic emergency equipment is not effected.

Such an arrangement is shown diagrammatically in Figs. 13 and 14 for use on a car of the mono-rail type shown in Fig. 12. Fig. 14 is intended to show in diagram an automatic emergency equipment to operate in conjunction with this system of signals

and stop levers. The equipment consists essentially of an air valve 12 having operating handle 14 projecting normally vertically downward, a circuit closing disk switch 19, circuit breaker trip coil 20, circuit closing switch 30, and valve resetting electromagnet 31. It will be observed that handle 14 of valve 12 will engage lever 240 if the movement of the car is to the left, thereby turning handle 14 to the right. When this is done a passage for the compressed air stored in reservoir line 35 is allowed to escape comparatively slowly through pressure regulating valve 36 until the pressure in the reservoir line has been reduced to such a value that the moving element of emergency valve 38 will connect brake cylinder 39 with the compressed air reservoir 40 by means of pipes 44 and 45.

The amount of opening provided by emergency valve 38 is, to a certain extent, inversely proportional to the pressure in reservoir line 35. Hence if the pressure regulating valve 36 has been previously set correctly, the pressure in reservoir line 35 will decrease to that value, at which air will flow into brake cylinder 39 at such a rate as to best effect the stoppage of the car or train by means of the air brake equipment. Pressure regulating valve 36 is essentially a so-called safety valve provided with a suitable means for obtaining a fine adjustment of the pressure at which it will allow air to escape through it to the atmosphere. It is intended that the diagram representing the air brake equipment in Fig. 14 shall represent what is known as the emergency straight air brake system. Fig. 13 is a top view of truck 69 showing the connection between rods 70, 73 and 75 made by means of layers 76 and 77.

The mechanical equipment of valve 12 is such that whenever handle 14 is operated either to the right or left, the disk switch 19 will close two electric circuits. The first of these is from wire 46 on the motor side of the main circuit breaker 47 through solenoid 20, wire 48, small contact disk of switch 19, to the frame of the car, and from thence to the rails through which the current returns to the source. The second is from wire 49 connected directly to the trolley, or contact shoe, if a third rail system is used, through wire 50, electromagnet brake 55, wire 53, through the larger contact disk of switch 19 to the frame of the car, thence to the rails and back to the source of supply. The first circuit allows current to energize coil 20, which raises the iron plunger 57, which in turn trips circuit breaker 47, thus turning off current to the motors used to drive the car. The second energizes the electromagnet brake 55 which operates in conjunction with, or in addition to, the air brakes 78 originally provided. It

is intended that the result shall be a quick, but not violent, stopping of the car, and it is expected that the necessary adjustments shall be made in order to insure such operation before the stop equipment shall be relied upon to bring the car to a stop in cases of emergency.

Before the car can proceed after being brought to a stop by the emergency equipment, the two electric circuits mentioned must be opened by means of switch 19, and handle 14 of valve 12 must be returned to the vertical position. This is effected by means of a third electric circuit from wire 49 through switch 30, wire 58, electromagnet 31 to the frame of the car and thence back to the source of supply. When electromagnet 31 is energized, switch 19 is opened and handle 14 returned to the vertical position if turned to the right or left. The last named circuit is complete only while switch 30 is held closed. After opening switch 19 and re-setting valve 12 by momentarily closing switch 30, the motorman with controller handle placed in the off position can then re-set circuit breaker 47. He may then release the air brakes by moving the handle of his air valve 59 to the emergency release position. In this position, valve 59 connects reservoir line 35 through pipe 66 to the main air reservoir 40, thus restoring pressure in reservoir line 35, which pressure then forces the moving element of emergency valve 38 in such a position that brake cylinder 39 is connected to train line 67 through pipes 45 and 68. With the motorman's air valve 59 in the emergency release position, the train line is opened to the atmosphere, thereby releasing the brakes. The car may then proceed as before.

The automatic stop levers, one of which is indicated by 240 in Fig. 14, are arranged one on each side of the track so that only one set of emergency equipment, as previously described, is required per car or train. In case the car was to operate end for end in either direction along the track, the automatic stop lever on the opposite side of the track, instead of lever 240 of Fig. 14, would engage valve handle 14, thus insuring a stoppage of the car under emergency conditions no matter on which side of the car the valve 12 and switch 19 may be mounted.

Referring to the signal system, all figures except 12, 13 and 14, the numbers below 100 indicate similar parts at each of the several stations. The digit or digits in the hundreds position of the designating numerals indicate the station to which that part belongs. For instance, referring to Fig. 16, 201 is a local semaphore battery for semaphore station 200, while 301 is the local semaphore battery for semaphore station 300, and 401 is the local semaphore battery for semaphore station 400. In this figure,

240 are the automatic stop levers which are indicated diagrammatically, one of which is shown in Fig. 14. 242 and 237 are pivotal points for these levers indicated by 242 in Fig. 14. 239 and 235 are rods for actuating these levers, one of which is indicated by 239 in Fig. 14. A third lever 232 pivoted at 233 works through these rods to set the automatic stop levers to either the clear or danger position. Rods 231 and 237 in conjunction with bell crank 229, which is pivoted at 228, serve to connect the system of levers referred to with a crank pin 224 mounted on a sprocket wheel 223 forming part of the semaphore operating mechanism. This arrangement provides a danger position of the automatic stop levers by placing the stop levers in the vertical position. When the semaphore mechanism is operated to give a clear indication of the semaphore, these levers are rotated about their pivotal points in an outward direction from the track so that the operating handle 14 of valve 12 in Fig. 14 will be unable to engage either one of the levers. As previously stated, the semaphore arm 200 is actuated by means of an electric motor through a reliable mechanical drive train such as a train of gears, or sprocket and chain, or combination of the two. These simple diagrams, as Fig. 16, indicate a sprocket 221, sprocket chain 222 and sprocket wheel 223 to effect the proper mechanical connection between the motor and the semaphore operating mechanism. The semaphore arm itself 200 is pivoted at 226. At one end 230 it is shown connected by rod 225 to the crank on the sprocket wheel 224. It is thus seen that when crank 224 is in the higher position, the semaphore arm is dropped to give a clear indication, while levers 227, 231, 235 and 239, bell crank 229 and the pivoted lever 232 place the automatic stop levers in the indicated clear position as shown for this semaphore station. This forms a simple and reliable connection between these two very important elements of the system and there is little chance of the semaphore indicating one condition when the automatic stops are set for a contrary condition of the track ahead of the moving car.

Figs. 2, 4, 6 and 8 illustrate the fundamental electric circuits involved to bring about various semaphore positions as indicated in Figs. 1, 3, 5 and 7, respectively.

Figs. 15, 17, 19, 21 and 23 correspond respectively to stations 200, 300 and 400 of Figs. 1, 3, 5 and 7, while Figs. 16, 18, 20, 22 and 24 show the electrical connections actually used in the primary relay and semaphore station circuits for the cases previously cited. For the position of the car indicated in Fig. 15, that is between semaphore stations 100 and 200 with the car approaching station 200, the circuit energized

will consist of battery 21, reversing switch 180, connecting wires 51 and 61, reversing switch 280, battery 22, and relay coils 71 and 41. The result is a clear signal in front 5 of the car due to relay armature 203 being raised by the magnetization of the relay core by coil 41. As has previously been shown, whenever the primary relay armature connects with the upper contact 204, the result is a clear semaphore station with the automatic stop levers in the outward position so that the emergency valve Q of Fig. 14 mounted on the side of the car will not be engaged as the car passes that station. In 10 Fig. 17 the car has actuated reversing switch 280 in passing semaphore station 200 and is approaching semaphore station 300. The operation of reversing switch 280 shifts the effective primary relay circuit from between stations 100 and 200 to between stations 200 and 300. The new circuit consists of battery 22, reversing switch 280, relay winding 32, wire 62, relay winding 42, reversing switch 380, battery 23 and wire 52. The result is the raising of relay armature 303 to the top contact 304 at station 300 and the maintaining still of relay armature 203 against contact 204, these relay armature positions giving clear semaphore signals. In each of the cases cited, arrows indicate the direction of current flow through the primary relay circuits. The arrows are omitted in all circuits which are not carrying current.

Fig. 19 is a continuation of Fig. 17 used to show the electrical circuits involved for a new position of the car which is now between semaphore stations 300 and 400. By Fig. 20 it will be seen that the previous circuit effective between semaphore stations is now dead electrically and a new circuit is provided between semaphore stations 300 and 400 consisting of battery 23, reverse switch 380, relay coil 33, wire 63, relay coil 43, reversing switch 480, battery 24 and wire 53. Fig. 21 indicates that the car has left the section of track between stations 300 and 400 and has reversed battery 24 by means of reversing switch 480. The result is that the primary relay circuit just described is now ineffective because of the direction of the electromotive forces due to batteries 23 and 24. A new circuit, however, is provided, consisting of battery 24, reversing switch 480, relay coil 34, wire 64, relay coil 72, Fig. 1, wire 65, battery 25 and wire 54. This results in the placing to danger of all semaphores other than those between which the car is operating. In fact we can see that as the car proceeds along a signalized section of track that it maintains two and two only of the semaphores in the clear position. These semaphores are located one in front of and the other behind the car. As the car leaves the electrici-

fied section of track under discussion, switch 580 will be operated, which reverses battery 25, thereby making the electromotive force of battery 25 oppose that of battery 24. The result is zero current flow, the dropping of relay armatures 403 and 503 to the lower contacts which effects danger indications of the respective semaphore arms.

Fig. 23 is merely a reproduction of Fig. 7. Fig. 24 shows the complete primary relay circuit connections required to effect the indicated semaphore positions. The arrows indicate the direction of current flow through the two circuits involved.

Where trains are required to operate in opposite directions over the same track sections, using turnouts or side tracks at intervals along the main line, it is necessary that the semaphore stations be so placed and operated that when two cars approaching each other come within dangerous proximity of one another there will be two semaphore stations effective between the approaching trains or cars. The distance between these stations must be such that under the most unfavorable circumstances it will be impossible for the two cars to collide. This is effected in this system by the use of so-called secondary relay circuits, and the simultaneous operation of two or more semaphore stations in conjunction with each primary relay battery station and reversing switch, there being in all cases a reversing switch for each primary relay circuit battery.

Fig. 25 is intended to indicate the most unfavorable condition of operation; namely, two cars approaching each other at exactly the same speed. Both have actuated the battery reversing switches last passed at the same instant. As the diagram indicates, semaphore stations 800 and 900 are at danger. Both will be stopped automatically should they attempt to pass these stations. The distance between stations would be ample to bring the cars to a complete stop before they can collide. Fig. 26 shows in detail the electrical connections required to make this arrangement of the semaphore stations possible. It will be noticed that the battery reversing switches are no longer placed at the semaphore stations but are mid-way between the two semaphores controlled from the respective primary circuit relay. For instance, reversing switch 880 is mid-way between semaphores 800 and 900. The diagram shows that when the current flow is as indicated, due to the reversing of batteries 26 and 28 relative to battery 27, relay armature 113 is in the closed position, resulting in the energizing of the simple relay coil 115, which in turn raises armature 703 against contact 704, giving a clear signal for that semaphore. The station preceding is also at the clear position because the

simple relay controlling that station is in parallel with the one described. It will be noticed that the only addition in this arrangement is the secondary relay circuit comprising, for stations 800 and 900, an additional battery 117, primary relay armature 118, contact 119, where the current would divide if the armature were raised. One of the divided circuits would be from contact 119 through simple relay coil 121 at station 900 line wire 122 and back to the negative terminal of battery 117. The other circuit is from contact 119, line wire 124, simple relay coil 123 at station 800 and back to the negative terminal of battery 117. This constitutes a circuit complete in itself in every detail. It will be noticed that instead of the primary relay armature controlling the position of the semaphore arm by closing the different local semaphore circuits, these circuits are now controlled by a simple relay at each semaphore station which in turn are controlled by the primary circuit relay located at the battery reversing switch between the semaphore stations. Primary relay armature 118 is in the opened position because the primary relay circuits are energized as indicated by the arrows. The result of course is that the simple relay armature 803 and 903 at semaphore stations 800 and 900 respectively are allowed to drop to lower contacts 819 and 919, which results in a danger indication of the semaphore arms as previously described. Between semaphore stations 1000 and 1100 of Fig. 26 is shown a secondary relay circuit energized by the same battery that is used to energize the primary relay circuit. This is permissible since the two circuits are in no way connected electrically except through the battery which supplies current to both. The arrangement shown, however, is that of a series circuit as far as the semaphore relays, source of supply, and primary relay armature are concerned. The secondary relay arrangement between semaphore station 700 and the preceding one 600 is one which is thought to be the most practical of the two. In this case we have all the advantages of a parallel connection of the two semaphore relays with reference to the source of supply without the disadvantage of an additional battery to energize the secondary circuit relays. In this case it will be noticed that battery 36 supplies current to operate the secondary relay circuit as well as the primary relay circuit, the secondary relays being connected in parallel with reference to the source of supply. With this arrangement or that indicated for stations 800 and 900 in case one of the semaphore relay circuits becomes open for any reason, it is the only one affected. With this arrangement it is evident that any number of semaphore stations may be operated simultaneously from the same primary circuit relay. Thus the system adapts itself admirably to a wide range of track semaphore requirements made evident by the operating requirements of the road.

Figs. 27 and 28 indicate the relative positions of battery reversing semaphore stations at the beginning, intermediate stations, and end of a track section signalized by secondary relay controlled semaphores. It will be noticed that the relative arrangement of primary relay battery 21, reversing switch 180 and semaphore station 100 are the same as indicated in Fig. 1 for the more simple arrangement. At station 100 the primary relay controls the semaphore circuits direct. At stations 600 and 700, however, the semaphore positions are controlled by simple relays which in turn are controlled by the differential relay in the primary relay circuit located mid-way between the semaphore stations near battery reversing switch 680. At the end of the signalized track section the arrangement of semaphore station and battery reversing switch is the same as at the end of the section indicated in Fig. 1. These circuits are complete in every detail and will serve to show the electrical connections required not only for the intermediate stations, such as 600, 700, 800, 900, 1000 and 1100 of Figs. 25 and 26, but also the connections required at the ends of such a signalized section.

To be effective, a signal system of this nature must be capable of interacting with control circuits which may be independent of the signal system proper. For instance, in the case of moving track sections, such as draws, turntables, or switches, it is necessary that when these parts are in a dangerous position that proper indication of such position be shown at semaphore stations located at either side of the track section mentioned. Figs. 29 and 30 show a signal system in which the semaphores are controlled directly by the differential primary circuit relays at stations 1400 and 1500, then by means of simple secondary relays at stations 1600 and 1700. The two different signal circuit arrangements are included to show the flexibility of this method of interaction with additional control circuits. Fig. 29 shows a lift in a raised position. It will be noticed that semaphore stations 1500 and 1600 indicate danger. The car shown approaching this lift will be stopped at station 1500 should it attempt to pass in spite of the danger indication. Should the car now moving towards station 1700 attempt to back into the open lift, it will be stopped at semaphore station 1600 although in backing it would actuate battery reversing switch 1640 which might be expected to operate semaphore 1600 to the clear position. It will be noticed, however, in tracing the elec-

trical circuits of semaphore stations 1500 and 1600, that an additional relay has been provided at each of these stations. The coils of these relays are included in a circuit consisting of a separate and independent battery 1852 of the closed circuit type, wire 1851, switch 1850, wire 1848, switch 1847, wire 1846, relay coil 1845, wire 1855, relay coil 1854 and wire 1853. This circuit is normally closed when the track section is in a safe position and the locking device closed, for then switch 1850 and switch 1847 are both closed. In case either one of these are not in a fully closed position, the circuit just described will be open and relay armatures 1542 and 1642 will provide a circuit through the semaphore operating motors which will in all cases give a danger indication of the semaphores regardless of the position of the primary circuit relay as shown at station 1500 or the secondary circuit relay as shown at station 1600. A careful tracing of the circuits at these stations will show that in either case the relays used ordinarily to control the semaphore arm positions are effective in the circuit only when the auxiliary circuit relay armatures are in the raised position, corresponding to a closed auxiliary control circuit which is energized continuously when closed by a battery of the closed circuit type previously referred to as 1852. It is evident that in case this circuit is interrupted in any way, due to failure of the circuit closing switches 1850 or 1847, breakage of the line wires or other accidental or intended openings in the circuit, the semaphore stations under the control of this circuit, no matter what their number, will at once indicate danger, thus reducing to a minimum any uncertainty in the operation of such an important addition to the signal circuits proper. It is evident that any number of circuit closing switches, which must be closed in order to indicate a safe condition of the track section, may be inserted in this circuit, any one of which is as effective as the others in controlling the semaphore station operations, therefore, insuring that every item which is supposed to be operated to give this safe condition to the track section is in the required position before clear signals can be obtained at the semaphore stations on either side of the movable track section.

Obviously, changes in the details of construction can be made within the scope of the following claims.

What we claim as new, and desire to protect by Letters Patent, is:—

60 1. An automatic signal system for rail-

ways comprising a series of semaphore arm signals disposed along the track of said railway, local circuits for each of said semaphore arm signals, primary relay circuits provided with simple and differentially wound relays for controlling said local circuits, a series of batteries for said primary relay circuits disposed at selected points along said railway, motors provided with limit switches for actuating said semaphore arm signals, switches operatively connected to said batteries, and means provided on the cars of said railways for engaging said switches and reversing the terminals of said batteries whereby said motors will be started and said limit switches will be caused to automatically break the circuit to and arrest said motors and provide circuits through the motor windings upon the completion of the new position of the semaphore arms whereupon when the original relay connections are made said motors will return the semaphore arms to their original positions and cause the said limit switches to be returned to their original positions. 85

2. In combination with a car an automatic signal system and train stop for railways comprising a series of semaphore signals disposed along the tracks of said railways and provided with impact members controlled by the clear and danger signals of said semaphores, emergency switch mechanism provided on said car for actuating said car brake mechanism, local circuits for each of said semaphore signals, primary relay circuits provided with simple and differentially wound relays for controlling said local circuits, a series of batteries for said primary relay circuits disposed at selected points along said railways, motors adapted to actuate said semaphore signals, switches operatively connected to said batteries and impact members provided on said car for engaging said switches and reversing the terminals of said batteries whereby said semaphore signals will be actuated to register the clear or danger signals, and whereby said emergency switch mechanism will be actuated by the impact members provided on said semaphores should said car attempt to pass said semaphores when set at the danger signal. 105
